ORNAMENTAL KEY HOLD FOR HANDBAGS

Nell L. Fulton, New York, N. Y.

Application May 27, 1941, Serial No. 395,467

4 Claims. (Cl. 24—3)

The present invention relates to improvements in ornamental key holds for handbags which are carried particularly by ladies, and the invention has for its primary object to provide a device, in the nature of an attachment to the handbag, for supporting a key, for instance the key of the house residence front door, in a position always accessible for detachment and use in opening such front door, as when the proprietress returns from a shopping tour downtown laden with bundles of purchases.

The invention has for its additional purpose the provision of a key hold for ladies' handbags which will present the key at all times to the proprietress of the bag in the same known position elevated above the bottom of the bag to dispense with entirely the rummaging through the miscellaneous articles in the bottom of the bag in order by process of elimination to sort out and isolate the wanted key, which process must always be conducted under the disadvantageous circumstance of generally having only one hand for the purpose, the other being occupied with bundles or the like.

A further object of the invention is to provide an improved key hold susceptible of receiving an ornamental characteristic.

A still further object of the invention resides in providing an improved key hold in which facility in the attachment of the key hold to the handbag is promoted, and wherein the attachment of the key hold is made more secure, at the same time cooperating with the hook of the key hold to hold the hook more tightly closed but at the same time enabling the more ready opening of the hook in the acts of inserting or removing the key.

A still further object of the invention resides in certain constructional characteristics of the key hold, in the initial formation of the blank from which the same is fashioned, in the new and more efficient cooperation of the improved key hold with the partition or wall of the handbag to prevent its accidental removal therefrom and to maintain the same in place, and in certain improvements in the hook and its cooperation with the key hold.

With the foregoing and other objects in view, the invention will be more fully described hereinafter, and will be more particularly pointed out in the claims appended hereto.

In the drawing, wherein like symbols refer to like or corresponding parts throughout the several views—

Figure 1 is a perspective view of an improved 55

ornamental key hold constructed in accordance with the present invention and shown as applied to a wall of a handbag indicated in dotted lines.

Figure 2 is a side edge view of the same, with parts broken away and parts shown in section, and

Figure 3 is a plan view of the blank employed.

Referring more particularly to the drawing, the device is preferably made from a thin flat piece of spring steel or brass having a strong spring action and is composed generally of a back wall 10 and a front wall composed of an upper section 11 and a lower section 12. The lower section 12 is substantially parallel with the back wall 10 and will lie substantially in contact with the front surface of the back wall 10 when the device is in the condition shown in Figure 2; that is when it is detached from the handbag and under the influence of its own inherent resiliency. The upper section 11 of the front wall is also substantially parallel with the upper part of the back wall 10 but spaced forwardly therefrom.

25 The bight or hinge connection 13 is the fold line on which the metallic strip forming the blank shown in Figure 3 is bent to secure the rear and the front walls referred to. This bight is open, that is spaced from both front and back walls in order to permit freedom of movement of the two walls in spring apart or together.

20 The hook for the key is shown at 14, and as having a lip 15 which lip is bent in a curved sweep outwardly and downwardly from the upper end of the hook 14.

35 Shoulders 16 and 17 are incorporated in the construction. The shoulder 16 connects the two sections 11 and 12 of the front wall. The shoulder 17 comes downwardly and forwardly off the lower end of the back wall 10 and into the pilot foot 18 which extends below the intermediate part of the hook 14. Between the upper end of the incurving hook 14 and the outwardly curved lip 15 is a curved cheek 19 adapted to lie against and beneath the shoulder 16. The rear portion of the lip 15 rises to a high point 20. This point 20 is high in relation to the parts 16 and 19 so that when a key is forced downwardly the high point will rather guide the key into a throat between the parts 16 and 19, thus prying open the hook and enabling the key to enter the key hold hook 14 rather than depressing the free end of the lip 15 which would cause the key to slide outwardly in the opposite direction. Spurs 21 and 22 are carried respectively by the

back wall 10 and the shoulder 17. The pointed end of the spur 21 is received in a forwardly offset enclosed dome 23 of the front wall lower section 12. The free end of the spur 22 is received in or through a perforation 24 formed in the base of the hook 14. These spurs are preferably triangular in shape, as indicated in Figure 3, connected by their basal lines with the metal strip and foldable on such long basal lines, and with the apexes thereof, constituting the prongs, directed outwardly at their free edges in order to bite into the cloth of the wall of the handbag. Such prongs are given an initial diagonal bend outwardly and forwardly from the back wall 10 as seen in Figure 2. The prong 21 extends forwardly towards the dome 23. The prong or spur 22 extends upwardly and into the perforation 24.

The base of the hook 14 adjoining the shoulder 17 extends to a low point 25. This point 25 is low with respect to the shoulder 17 in order to guide the cloth into the throat between the shoulder 24 and base of the hook 14 and to cause the cloth or other material of the partition wall to be directed between the front and back walls of the device. If it were not for this low point 25 in the curvature of the lower base part of the hook 14, the edge of the partition wall over which it was sought to insert the device might conceivably be directed outwardly to the outer side of the hook 14 by reason of the curvature thereof.

The pilot foot is rounded at its lower edge as indicated at 26 to facilitate the application of the device to the handbag partition.

An ornament is indicated at 27 as being incorporated in the metallic article. This ornament may be made integral with the strip or the strip may be enlarged at this point and a separate monogram or other ornamental device applied thereto in any suitable manner such as by soldering, brazing, etc.

The partition wall of the handbag is indicated in dotted lines at 28.

In manufacture, the device may be conveniently and economically stamped out in great numbers in the substantially flat form indicated in Figure 3 at which time the prongs and dome 23 may be struck up and the perforation 24 pierced. Thereupon, the device is folded on the bight line 13 in proximity to the ornament 27 to form the front and rear walls with the ornament 27 occupying a prominent position upon the outer offset front wall upper section 11. Upon this section 11 the ornament 27 is in an intermediate position spaced above the throat 16, 19, therefore not interfering with the attachment and removal of the key; and spaced below the bight 13 so as not to interfere with the free relative flexing of the front and rear walls of the device in the act of applying the device over the wall 28 or removing it therefrom.

The shoulders 16 and 17 are offset and the key hook 14 and lip 15 bent to shape. The prongs or spurs will automatically take up the positions indicated in Figure 2 and the wings or arms of the ornament 27 may be bent into a suitable artistic position.

In use, the device is inserted downwardly over the partition 28. In this act, the pilot foot 18 serves to correctly place the device initially by locating such pilot foot on the inside of the partition 28. The pilot foot also serves the function of guiding the device downwardly while maintaining it in its true position. The upper edge

of the wall 28 encounters the low point 25 and is guided thereby into the throat 17 which is curved backwardly and thereby causes the partition 28 to acquire an offset 29 which tends to hold the device in place. As the device slips down over the partition the prongs 21 and 22 will be guided back into the planes of the back wall 10 and shoulder 17. However these prongs will bite into the fabric material of wall 28 and prevent the device being pulled upwardly therefrom, except when the front and rear walls are pried far apart, which may be conveniently done by grasping the pilot foot 18 in one hand and the loop of the hook 14 in the other. The enclosed dome 23 will receive the pointed end of the prong 21 and shield it so that it will not prick the hand of the proprietress of the bag. A similar dome may be formed about the opening 24 if desired, although at this point the prong is shielded by the bow of the hook 14. It will be noted that the prong 21 bites forwardly into the fabric of the wall 28 while the cooperating prong 22 bites upwardly into the offset portion 29 at substantially right angles to the action of the companion prong 21. In this way, the shoulder 17 has a three-fold function; first, to form the offset 29; secondly, to form a member of the lower throat; and thirdly, by its inclination to hold the prong 22 at an angle to the effective action of the companion prong 21. Therefore the offsetting of shoulder 17 cooperates with both of the prongs in a new relationship, all of which contributes to the initial placing of the holding of the article finally upon the bag wall 28.

The key may be simply thrust against the side of the high point 20 and forced inwardly and downwardly, which will cause it to pry out the cheek 19 from the shoulder 16 and admit the key through the throat and onto the hook 14 where it will be retained in an elevated easily accessible position at all times where it is known to be by the proprietress of the bag. By the act of raising the key, it will be brought to the throat and by reason of the bowed portion of the hook 14 it will cause the cheek 19 to be pried outwardly, thus allowing of the escape of the key.

When the cheek 19 is thus pried out, the action will be also to pry the same downwardly. This action will be communicated to the bow 14 and downwardly to the base of the hook. In this action the shoulder 17 cooperates in that it is placed to resist such downward action of the base of the hook 14. Thus the shoulder 17 contributes to hold the cheek 19 up against its upper shoulder 16 which is essential to a closed position of the hook. The presence of the shoulder 17 together with the formation of the base of the hook 14 and its low point 25 also tends to cause the cheek 19 to move horizontally outward from the shoulder 16 rather than downward which will better cooperate with the high point 20 to send the key inwardly of the hook rather than sliding in the other direction out upon the lip 15; and this compulsion to a horizontal movement in the cheek 19 will tend to better preserve the resiliency of the device and will serve to provide longer life in the device in that the cheek 19 will be prevented from having any tendencies to fall away from the shoulder 16. In fact, the lower shoulder 17 will tend to maintain the cheek 19 at all times up against the upper shoulder 16. The upper side of lip 15 forms a curved guiding surface for the key over the high point 20 into the throat 16, 19. The lip 15 is also so bent

as to provide a crook on its underside for the fingers to pull the cheek 19 horizontally outward to assist in either introducing or removing the key from the hook.

It is obvious that various changes and modifications may be made in the details of construction and design of the above specifically described embodiment of this invention without departing from the spirit thereof, such changes and modifications being restricted only by the scope of the following claims.

What is claimed is:

1. An improved key hold for handbags and the like comprising front and rear walls resiliently connected together at their upper ends and open at their lower ends to fit over a support, a key hook on the front wall, and a pilot member on the rear wall extending below the front wall and hook, said pilot member offset forwardly of the rear wall below the base of the hook, and extending from the offset portion substantially below the lowermost closed curved portion of the hook and front wall.

2. An improved key hold or the like comprising front and rear walls resiliently connected at their upper portions, a hook bent up from the front wall and having a wide rounded base portion, and a pilot member projecting down from the rear wall below the hook and having an offset shoulder underlying an intermediate portion of the rounded base of the hook, said pilot member extending down a substantial distance below the rounded base of the hook.

3. In a key hold or the like, a resilient metal thin flat strip stamped and bent to form front and rear walls with the front wall in offset sections with an intermediate shoulder, an ornament on the upper section of the front wall, a

hook on the lower section of the front wall with a rounded base, a curved cheek and a reversely curved lip, a pilot on the rear wall offset forwardly from the rear wall with a shoulder therebetween to react against the rounded base to cause the cheek to firmly engage the first shoulder, triangular spring spurs in the back wall and second shoulder lying angularly with relation to one another, an enclosed dome in the front wall to receive the point of one spur, the base of the hook having a perforation to freely receive the point of the other spur, said pilot having a rounded lower edge.

4. In a key hold or the like, front and rear members and a hook of resilient one-piece material, said front member being biased by the inherent resiliency to a tight closed position against said rear member, said hook having a rounded bight connecting the same resiliently with the lower portion of the front member, said rear member having at its lower portion a downwardly and forwardly extending shoulder lying with resilient pressure against the rear portion only of said curved bight, a spur on said shoulder extending substantially upwardly and inclined towards the rear member, said bight having an opening to receive said spur, a second spur spaced from the first spur and extending upwardly and forwardly from the rear member, said front member within the hook having a dome to receive said second spur, a second shoulder spaced considerably above and opposed to the first-mentioned shoulder and formed in the front member extending forwardly and upwardly therefrom, and a rounded bill on the free end of said hook forced resiliently against said second shoulder.

NELL L. FULTON.
